Primary Examiner—Doris V. Coles

Attorney, Agent, or Firm—G. Davies Weber, Jr.

[57] **CLAIM**

The ornamental design for an automotive wheel, as shown and described.

DESCRIPTION

FIG. 1 is a perspective view of an automotive wheel, showing my new design; and,
FIG. 2 is a front view thereof.

The broken line showing of environment is for illustrative purposes only and forms no part of the claimed design.
